UNITED STATES PATENT OFFICE.

CHARLES E. BRADSHAW, OF WATERBURY, AND WILLIAM B. RUNK, OF DERBY, CONNECTICUT, ASSIGNEES TO THE ROBERT N. BASSETT COMPANY, OF SHELTON, CONNECTICUT, A CORPORATION OF CONNECTICUT.

WIRE-Straightening Machine.

1,145,345.

Specification of Letters Patent.

Patented July 6, 1915.

Application filed November 28, 1913. Serial No. 803,592.

To all whom it may concern:

Be it known that we, CHARLES E. BRADSHAW, a resident of Waterbury, in the county of New Haven and State of Connecticut, and 5 ⁵ WILLIAM B. RUNK, a resident of Derby, in the town of Derby, in the same county and State, have invented a certain new and useful Improvement in Wire-Straightening Machines, of which the following is a specification.

10 Our invention relates to wire straightening machines and more particularly to that class of the same in which the wire is given a lateral bend by a guide which revolves around the wire during its passage through the machine, thereby bending it radially in all directions around its axis; and its object is to provide a device of this character in which the guide, or guides, is so mounted 15 as to exert the least tendency toward a torsional strain on the wire.

20 A further object of our invention is to provide longitudinal and transverse adjusting means for changing the angle of the bend in the wire as it passes around the guide or guides, thereby enabling the machine not only to accommodate itself to wires of different character but also to wires of different gages.

25 30 We attain these and other objects of our invention in the machine set forth in the following description and accompanying drawings in which like reference characters refer to corresponding parts.

35 40 In the drawings: Figure 1 is a top view of the machine, parts thereof being broken away; Fig. 2, an end view; Fig. 3, a transverse sectional view taken on line $x-x$ in Fig. 1; and Fig. 4, an enlarged transverse sectional view of the guiding stud.

45 Our invention generally consists of a bed or frame A having mounted to revolve therein a mandrel B. The bed A is skeleton in form and consists of the side bars 2, 2 and the end bars 3, 3. Projecting from the corners of the bed are the feet 4 by means of which the bed may be fastened down by the cap screws 5. The mandrel B comprises the side bars 6, 6 connected at their extremi-

ties to form a skeleton frame 8 having an elongated opening 9. A pulley 10, provided with flanges 11, 11, projects from one end of the frame 8, and from each extremity of the mandrel projects the journals 12, one of which appears in section in Fig. 1. The end bars 3, 3 are machined or bored to form bearing seats for the journals 12. The bearings may be opened by removing the cap screws 13, 13 and lifting off the cap plates 14, 14, a construction well known in journal bearings. All of the parts of the bed A with the exception of the cap plates and all of the parts of the mandrel B may be made respectively out of a single piece or casting. The mandrel B is bored axially from end to end to form an opening 15 and for the insertion of the hollow tubes 16, 16 which hereinafter will be styled as quills or guides. The outer extremity of each quill 16 is knurled to form a thumb piece 17 and adjacent to the thumb piece for some distance along the face of the quill are cut screw threads 18 which are of less diameter than the opening in the mandrel, thereby permitting the latter to revolve around the quills which latter are held stationary in the internally threaded supporting plates 19, 19. Each of these supporting plates is fastened to the end bars 3, 3 of the bed A by the cap screws 20, 20. The quills 16, 16 project into the opening 9 of the frame 8 and may be adjusted longitudinally by screwing the same back and forth through their respective supporting plates 19, 19. The screw threaded portion of each quill which projects outwardly beyond its supporting plate carries a nut 21 for locking the quill in its adjusted position. The frame 8 of the mandrel has its side bars 6, 6 bored transversely midway of their extremities to form seats for the guide stud 22 one of these seats 23 being shown in Figs. 1 and 3. The guide stud 22 is provided with a diametrically disposed slot 24 midway between its extremities and in this slot is journaled the cone ball bearing 95 guide roller 25 having its periphery cut to form a guide channel 26 for the wire.

The cone ball bearings are constructed in

- the following manner (see Fig. 4): The guide stud 22 is bored at right angles to the plane of the slot 24 to form a bore 27 for the insertion of the cone screw 28 which has 5 its head beveled on its under side to form the cone 29. The bore 27 is provided with a seat in which sets the internally screw threaded cone 30 and through which latter passes the shank 31 of the cone screw 28.
- 10 The roller 25 is provided with an opening greater than the diameters of the head of the cone screw 28 and the cone 30 the internal face of which opening is cut to form reverse cones 32, 32.
- 15 To assemble the parts the roller 25 is inserted in the slot 24 so that its central opening will register with the bore 27 in the guide stud 22, then the cone 30 is dropped into its seat in the bore 27. The balls 33 are 20 then dropped into the bore 27 where they rest upon the cones 30 and 32. The cone screw 28 is then inserted in the bore so that its cone 29 rests on the balls. Thus assembled, the cones 29 and 30 coöperate respectively with the reversed cones 32, 32 of the 25 roller to form seats for the balls 33. The bearings may be adjusted, that is tightened or loosened, by screwing the cone screw 28 back and forth through the cone 30. When 30 the adjustment is once effected it may be set by the lock nut 34 which is screwed over the extremity of the shank 31 of the cone screw. The guide stud may be adjusted transversely through the seats 23 of the 35 mandrel by means of the locking screw 35.
- To thread the wire prior to operating the machine the extremity is passed through one of the quills from its outer end then through the guide stud 22 which latter may be set 40 so that the opening formed by the channel 26 in the guide roller and the adjacent extremity of the slot 24 is in alinement with the axis of the bore in the quills; then the wire is passed through the bore in the other 45 quill and outwardly into a wire working machine or upon the ordinary drawing table the wire being fed by any suitable means. The quills being in alinement with each other and the guide stud being so set that 50 the wire may be passed therethrough without giving any bend thereto the threading of the wire is greatly facilitated. After the threading of the wire is effected the guide stud is then adjusted transversely of the 55 mandrel and the quills adjusted longitudinally thereof to give the desired angle and length to the bend. The inner extremity of each quill has its bore flared outwardly to 60 present a smooth bearing surface to the wire. Since the quills are fixed relative to the revolving movement of the mandrel any torsional strain in one direction exerted by the wall of the channel 26 of the roller is

counteracted by the torsional strain in the other direction exerted by the bearing surfaces in the flared extremities of the quills. The traction of the wire causes the guide roller 25 to revolve on its bearings so that this taken together with the elimination of the torsional strain above referred to enables a rolling contact to be effected between the roller and the wire, thereby reducing the load on the machine. This manner of mounting the roller guide gives to the wire a very high polish free from all scratches or other objectionable marks thus making the machine particularly adapted to straighten soft wires. Since the cones of the bearings are adjustable the balls are permitted more or less play in their seats so that the roller may yield slightly against the centrifugal force exerted on the balls when the roller is revolved bodily by the mandrel. If desired a plurality of guide studs may be employed in which case the mandrel frame may be lengthened.

Having now described our invention what we claim and desire to protect by Letters Patent is:

1. In a wire straightening machine, a bed or frame carrying an axially bored mandrel, a pair of apertured internally screw threaded supporting plates secured to the ends of said frame and a pair of externally screw threaded quills of less diameter than said bore, the said quills being fitted to the apertures in said plates and extended through said bore, whereby a longitudinal adjustment of the quills may be effected by axially turning the same in their respective plates. 90
2. In a wire straightening machine a revoluble mandrel, an adjustable guide member carried by said mandrel, the said guide member being provided with a slot disposed in a direction radial to the axis of the mandrel, a centrally apertured guide roller located in said slot, the wall of the aperture in said roller being circumferentially recessed to present a bearing surface, a pair of inverted cones mounted in said guide member, the said cones being extended into the aperture in the roller forming a raceway between the cones and the wall of the aperture, and a series of balls carried by said raceway. 95
3. In a wire straightening machine a revoluble mandrel, an adjustable guide member carried by said mandrel, the said guide member being provided with a slot disposed in a direction radial to the axis of the mandrel, an antifriction centrally apertured guide roller located in said slot, the wall of the aperture in said roller being circumferentially recessed to present a bearing surface, a pair of inverted cones one of which 100 is seated on one side of said roller and the

other adjustably mounted relatively to the first mentioned cone on the other side of said roller, the said cones being extended into the aperture in the roller forming a raceway between the cones and the wall of the said aperture, and a series of balls carried by said raceway.

5 In testimony whereof we have hereunto

set our hands this 8th day of September, 1913.

CHARLES E. BRADSHAW.
